ABSTRACT

Rolled or machine-cut gears are finished by a rolling action in engagement with a die roll comprising a guide gear intermediate a pair of side gears. The outer gears form chamfers on the tooth edges while the guide gear, when working without flank clearance against the work gear, prevents flank bulging and effects smoothing. The teeth of the work gear are substantially confined by the teeth of the three gears of the die roll to prevent bulging of material due to the effect of chamfering as well as effecting burr trimming and smoothing.

APPARATUS AND METHOD OF FINISHING GEAR TEETH

The art of finish rolling gears after having been initially forged or machine-cut, etc., has already been known. The general method is to roll or machine-cut the work gear to effect a preliminary forming of the teeth of the blank. Thereafter, however, a certain amount of finishing is required for the purpose of chamfering the edges of the work gear and also deburring the edges and smoothing the flanks. Various machines and methods have heretofore been known for performing these operations.

For example, it has been known to use a finishing die roll in conjunction with gears which are laterally disposed with respect to the die roll for effecting chamfering wherein the work gear must be axially shifted to come into engagement with each of the side die rolls for successively chamfering and trimming both acute-angled tooth corners of helical gear teeth. This arrangement caused bulging at the flanks of the work gear teeth because of flank clearance between the work gear and the die roll guide gear. The die roll did not prevent such bulging and as a result, additional operations were required for flank smoothing.

Another machine for chamfering and deburring heretofore known, dispenses with the guide gear but requires a separate motor for the work gear and for the chamfering and deburring gears. The chamfer angle must be limited to 35° to avoid bulging of material at the teeth flanks. Also, to maintain a certain width of chamfer, the rolling time must be limited. For the operation, special instrumentation is required.

Another machine for the purpose combines a motor-driven shaving gear with a guide gear both gears meshing with the work gear. The shaving gear removes bulged material affected by the chamfering action.

Briefly, the present invention avoids the drawbacks of the prior art by providing a composite die roll comprising a guide gear for meshing with teeth of a work gear to be finished and also comprising a chamfering gear on each side of said guide gear and secured thereto and having tooth ends at respective tooth ends of said guide gear with chamfering surfaces at an obtuse angle to said respective ends, whereby chamfering of tooth corners of said work gear is simultaneously effected by said chamfering surfaces when said die roll is rotated and by providing means for forcing said die roll into a relative radial movement towards said work gear, and wherein the teeth of said guide gear are formed to mesh with the teeth of said work gear fully across the flanks thereof and with zero flank clearance at the end of said radial movement.

A further embodiment of the invention provides a die roll with a guide gear the flanks of which are formed in such a manner and a predetermined force being applied to radially move said die roll towards said work and press the meshing flanks together such that the flanks of said work are simultaneously smoothed while respective tooth corners are being chamfered.

By providing a composite die roll of the kind described the chamfering, deburring, trimming and flank smoothing, all can take place simultaneously. Thus, by applying a confinement to the teeth of the work gear as they are being rolled against the teeth of the composite die roll, bulging of material at the flanks

of the work gear is avoided and no further operational step to remove bulging is necessary.

The invention is applicable to various types of gears, as will be described, and in a simple apparatus wherein the work gear is motor driven while the die roll is freely rotative and moved against the work gear by hydraulic power. Also, the invention is applicable to formed gear blanks not necessarily prepared by a rolling process but by means of milling, shaping, etc., wherein the invention is capable of a complete finishing operation.

The flanks of a guide gear intended to smooth the flanks of the work gear can be performed with a profile modification to anticipate a distortion occurring after heat treatment of the finished gears.

In the course of using the invention, rotational direction may be changed one or more times in order to yield the highest surface quality and dimensional precision. Further, contact pressure between the work gear and the die roll can be predeterminedly varied to achieve different effects for clockwise and counter-clockwise rotation.

A detailed description of the invention will now be given in combination with the appended drawing in which:

FIG. 1 is a fragmentary view of the meeting engagement of teeth of a work gear shown in section with teeth of a composite die roll showing the guide gear and the chamfer forming gears at the sides thereof, oriented at obtuse angles, the illustration being for helical teeth, the presentation of FIG. 1 being illustrative generally of a section on the line A—A of FIG. 4;

FIG. 2 is a view similar to FIG. 1 except that the chamfering die roll gears have teeth which are aligned with the teeth of the intermediate guide gear;

FIG. 3 is similar to the view of FIG. 2 except that the work gear has no helical tooth angle;

FIG. 4 shows in longitudinal section the essentials of an apparatus for carrying out the method of the invention;

FIG. 5 is a view similar to FIG. 2, except that all edges of helicoidal work gear teeth are chamfered.

Reference is now made to FIGS. 1 and 4, and referring initially to FIG. 1, a work gear to be finished is comprised of teeth 2 which will be understood to be in full mesh with teeth 1 of an intermediate gear of a composite die roll which intermediate gear is a guide gear and is rotated by the work gear, having zero flank clearance therewith. The die roll also comprises side or chamfering gears having respective teeth 3 and 4. The composite die roll is driven radially by hydraulic power into mesh with the power rotated work gear, as will be more clearly understood from FIG. 4. The chamfering gears comprising teeth 3 and 4 are securely fastened to the guide gear as shown in FIG. 4, and the chamfering teeth are at a helical angle β' with the die roll axis. The helical angle of the work gear teeth is shown as β . These angles may or may not be equal, but in any event the angles between teeth 1 and 3, and teeth 1 and 4 are obtuse, as shown on FIG. 1.

It should be noted that teeth 2 of the work gear are slightly greater in width than the width of the guide gear teeth 1 of the die roll to permit entry of the lateral ends of the chamfering teeth between work gear teeth.

Upon rotation of teeth 1 and teeth 2 with progressive radial movement of the die roll into mesh with the work

gear acute-angled corner edges 5 of the work gear teeth 2 will be chamfered at diagonally related corners, i.e., at the obtuse vertices interiorly of the angles at the contiguous ends of the guide gear and respective inner ends of the chamfering gears. Smoothing due to increased hydraulic pressure acting on the power rotated work gear is also effected, as well as burr trimming since each of the work gear tooth flank surfaces is being progressively acted on at the same time as the chamfering occurs, across the tooth. Reverse rotation may be had to further effect the smoothing process.

Upon completion of this operation, it is repeated with chamfering gears of a helix angle equal to that of the guide gear so as to chamfer the two other diagonally related corners of the work gear as described in detail in connection with FIG. 2 and FIG. 3. Thus, the chamfering gears are removable from the guide gear so that another pair of chamfering gears can be attached to the guide gear, as will be apparent from the showing in FIG. 4 for the chamfering gears 37 and 38 secured to guide gear 36 as by screws and pins.

Since the guide gear teeth extend the full width of the working flank surfaces of the work gear teeth full surface smoothing is achieved. Further, very precise smoothing can be effected by reverse rotation cycles at various speeds, and by virtue of the zero clearance the chamfered surface of the work gear corners is held to precise angles and areas.

Referring now to FIG. 2, the die roll guide gear teeth 11 are shown on opposite sides of a work gear tooth 12, as in FIG. 1, except that the chamfering teeth 13 and 14 are now aligned contiguously with respective guide gear teeth 11, and have obtuse angle chamfer surfaces circumferentially offset from the respective guide gear teeth. Thus, the edges or corners of the teeth 13 and 14 are chamfered as at 15 and 16 and offset is effected by making the chamfer gear teeth thicker than the guide gear teeth. Accordingly, although the angle β_0 is the same for all teeth, rotation and relative radial motion will cause chamfering of the work gear teeth at both acute-angled flank edges diagonally opposed to each other.

The chamfering of the work gear teeth is due to the fact that the teeth 13 and 14 are somewhat thicker than the teeth 11 and the flank of each tooth 13 is accordingly circumferentially offset, i.e., extending beyond the corresponding flank of respective tooth 11. There is an offset in the opposite direction between teeth 11 and 14. The increased flank thickness extending in opposite direction between teeth 13 and 14 with respect to the teeth 11 provides for the chamfering engagement as will be apparent from FIG. 2.

Substituting the gears 13 and 14 by chamfering gears of larger thickness the flanks of which are offset with respect to both flanks of the teeth 11 of the guide gear as represented in connection with straight spur gears on FIG. 3, will make the chamfered edges 16 to attack and chamfer the adjacent edges in the two other diagonal corners of the work teeth (see FIG. 5).

In FIG. 3, the method is used for straight teeth, all four corners 25 of work gear teeth 22 being chamfered simultaneously. In this case, the edges 25 of the chamfering die roll teeth 23 and 24 which face the work gear teeth 22 are all chamfered uniformly at an obtuse angle to the tooth flanks. The chamfer gear teeth are thicker

and symmetrically disposed with respect to the guide gear teeth 21 intermediate respective pairs of chamfer die roll teeth 23 and 24. It will thus be apparent that if the work gear and die roll are forced into meshing engagement and simultaneously rotated that all four chamfers 25 will be formed at the same time and in the same direction of rotation, although reverse rotation for flank smoothing by the guide gear may be had.

Referring now to FIG. 4, the apparatus depicted 10 comprises a base on which is carried a work gear 31 of width b which will be understood to have a claw-type ring 32 for keyed engagement with a hub 33 on a supporting flange 35 carried on the base and rotated as by a motor driven shaft 43. Work gear 31 can be secured 15 by a screw 34.

Carried on the base is a slideable carriage 40 in rails 39, reversibly actuated by a piston rod 41 powered by double ended hydraulic cylinder 42. The die roll comprising guide gear 36 and side gears 37 and 38 will be 20 understood to be a composite and integral assembly freely rotative on carriage 40.

The width b of the work gear is always somewhat greater than the width of the guide gear teeth 36 in 25 order to allow space for the action of the chamfering die rolls.

In the course of the operational cycle chamfering and deburring is effected by the chamfering die rolls and any bulging of material which might move by 30 plastic flow to the flanks of the work gear teeth in the vicinity of the chamfering is smoothed out by the action of the guide gear die roll. This is achieved by providing a zero flank clearance between the teeth of the work gear and the guide gear die roll in all embodiments of 35 the invention.

While it is contemplated that the invention will be used in conjunction with work gears prior to heat treatment it will, of course, be understood that the invention is not thus limited but could be used as a cold rolling 40 process also for gears made of self-hardening steels.

In particular, the confining effect of the arrangement of the composite die roll controls the flow of metal in the course of the chamfering operation so that the finished product needs no further machine processing.

We claim:

1. A die roll for finishing gears comprising a guide gear having teeth for meshing with teeth of a work gear to be finished and said guide gear teeth being smaller in width than said work gear teeth; said die roll also comprising a chamfering gear secured on each side of said guide gear and having chamfering teeth of greater thickness than said guide gear teeth and abutting respective teeth thereof to effect circumferential offset from the tooth flanks thereof; the teeth of said guide and chamfering gears being at the same helical angle; chamfered surfaces on the teeth of said chamfering gears at an obtuse angle to the helical angle of the guide gear teeth at respective ends thereof; whereby said chamfered surfaces engage the corners of said work gear teeth for chamfering corners simultaneously at both ends thereof as said die roll is rotated and moved radially into mesh with said work gear.

2. A die roll as set forth in claim 1, the said greater thickness of said chamfering gear teeth effecting circumferential offset of the flanks thereof in relation to the flanks of respective abutting teeth of the said guide gear in both circumferential directions.

3. A die roll as set forth in claim 1, said chamfering surfaces extending from the circumferentially offset flanks of said chamfering gears to the corners of the flanks of respective abutting guide gear teeth.

4. A die roll as set forth in claim 2, said chamfering surfaces extending from the circumferentially offset flanks of said chamfering gears to the corners of the flanks of respective abutting guide gear teeth.

5. A die roll for finishing gears comprising a guide gear having teeth for meshing with teeth of a work gear to be finished and said guide gear teeth being substantially the width of the working flanks of said work gear teeth; said die roll also comprising a chamfering gear secured on each side of said guide gear and having chamfering teeth of greater thickness than said guide gear teeth and abutting respective teeth thereof to ef-

fect circumferential offset from the tooth flanks thereof; the teeth of said guide and chamfering gears being at the same helical angle; chamfered surfaces on the teeth of said chamfering gears at an obtuse angle to the helical angle of the guide gear teeth at respective ends thereof; whereby said chamfered surfaces engage the corners of said work gear teeth for chamfering corners simultaneously at both ends thereof as said die roll is rotated and moved radially into mesh with said work gear; the teeth of said guide gear being formed to mesh with the teeth of said work gear up to zero flank clearance whereby the working flanks of said work gear are simultaneously smoothed while tooth corners thereof are being chamfered.
